UNITED STATES PATENT OFFICE.

HARRY MARTIN, OF BROOKLYN, NEW YORK.

SANITARY CONTAINER.

Application filed September 21, 1927. Serial No. 221,009.

This invention relates to sanitary containers which may be utilized as a receptacle for a toothbrush or may be adapted for any other purpose.

5 The primary object of the invention is to provide a cap acting as a closure for the receptacle and which functions as a container for a cartridge or cartridges or other devices or articles impregnated with sterilizing material, which, when the cap is in closed position on the receptacle, are exposed to the interior of the receptacle, and, when the cap is removed from the receptacle, are cut off or enclosed so as to prevent the escape of 10 gas or vapor from the sterilizing cartridges.

With these and other objects in view, the invention consists in certain novel features of construction and combinations and arrangements of parts which will be more fully 15 hereinafter described and pointed out in the claims.

In the accompanying drawings—

Figure 1 is a view showing my improved cap and receptacle with the cap removed;

25 Figure 2 is an inverted plan view of my improved cap, partly broken away, illustrating details of construction;

Figure 3 is an end view of the receptacle or container;

30 Figure 4 is a view similar to Figure 2 with the gasket removed and the cartridges in position;

Figure 5 is a view in section through the cap, the view being taken on the line 5—5 of Figure 4;

Figure 6 is a view in longitudinal section showing the cap in closed position on the container with the sterilizing cartridges exposed to the interior of the container;

40 Figure 7 is a perspective view of the rotary disk of the cap;

Figure 8 is a perspective view of the gasket employed in the cap.

1 represents a receptacle and 2 my improved cap. I shall refer to this part 2 as a "cap" with the understanding that I employ this term to include a closure cover or other analogous device adapted to close the end of the casing 1.

50 The casing 1 may be of glass of any desired shape, and I have illustrated the same of a size and shape to receive a toothbrush 3 although of course it is to be understood that the device may be employed for sterilizing any article.

On the open end of the casing or container

1 a milled ring 4 is secured and is provided around its outer edge with beveled lugs 5, as clearly shown. The cap 2 is of general cylindrical form having a closed upper end and 60 an open lower end, and may be milled or otherwise roughened, as shown at 6, to facilitate turning of the same.

Within the cover and intermediate the ends thereof a partition plate 7 is fixedly secured. 65 This plate 7 is shown as having countersunk openings 8 at opposite sides of its center to receive sterilizing cartridges 9 which are located in the chamber or space 10 in the upper or outer end of the cap.

70 A disk 11 is located against the face of plate 7 and is connected to the plate by a central rivet 12 which permits the disk a rotary or turning movement, and this disk 11 has openings 13 therein adapted to register with 75 the openings 8 to expose the cartridges and also adapted to be moved so as to cut off communication between the cartridges and the open end of the cap.

76 The disk 11 is made with a series of channel shaped fingers 14 located at the edges of the plate and of a size to receive the lugs 5 of the ring 4 of container 1, and the lower or inner edge of the cap is provided with inwardly projecting flanges 15 under which the 85 fingers 14 ride when the cap is in closed and secured position on the container, and these flanges 15 are spaced apart sufficiently to accommodate the fingers 14 between them to allow the cover to be removed from the container.

86 To limit the turning movement of the disk 11 and to insure a proper registration of the parts, the flanges 15 at one end are bent inwardly forming stops 15' which are engaged 95 by the fingers 14, as clearly indicated.

16 represents a gasket which is preferably of cork or other compressible more or less resilient material located against the disk 11 and having openings 17 therein adapted to 100 register with the openings in the disk and preferably connected by a slot or slit 18 which allows the entrance of a tool or fingernail to manipulate the disk and gasket when placing the same in position or removing them from 105 the cap.

The operation is as follows:

When the cap is removed from the receptacle or container, the disk 11 is turned to a position to cut off the cartridges 9 so as to 110 prevent the escape of the sterilizing gas or vapor. When the cap is inserted on the con-

tainer the channel-shaped fingers 14 are positioned over the lugs 5 and while pressure is applied to slightly compress the gasket 16 the cap is turned to bring the flanges 15 of the cap under the lugs 5 to securely hold the cap on the container. This movement causes the gasket 16 and the disk 11 to turn to bring the openings 17, 13 and 8 into register so that the interior of the container is exposed to the gas or vapor from the cartridges and the toothbrush or other article in the container is subjected to a sterilizing action while the container is tightly closed. When the cap is removed it is necessary to turn the same and in doing this the disk 11 operates to cut off the cartridges and prevent loss of gas and vapor.

It is of course to be understood that I do not limit myself to any particular number of cartridges as I may employ one or more as desired, nor do I limit myself to the specific details of construction but desire to cover broadly the idea as expressed, and hence I do not limit myself to the precise details set forth but consider myself at liberty to make such changes and alterations as fairly fall within the spirit and scope of the appended claims.

I claim:

1. The combination with a container, lugs on the container spaced apart, a cap, a partition plate in the cap having an opening therein adapted to receive a sterilizing cartridge, a disk mounted to turn on the cap, and channel-shaped fingers on the disk adapted to engage over the lugs whereby when the cap is turned on the container the disk will operate either to open communication between the cartridge and the container or close communication between the cartridge and the container.

2. The combination with a container, lugs on the container spaced apart, a cap, a partition plate in the cap having an opening therein adapted to receive a sterilizing cartridge, a disk mounted to turn on the cap, channel-shaped fingers on the disk adapted to engage over the lugs whereby when the cap is turned on the container the disk will

operate either to open communication between the cartridge and the container or close communication between the cartridge and the container, and flanges on the end of the cap adapted to engage under the lugs on the container to lock the cap in closed position on the container.

3. The combination with a container, lugs on the container spaced apart, a cap, a partition plate in the cap having an opening therein adapted to receive a sterilizing cartridge, a disk mounted to turn on the cap, channel-shaped fingers on the disk adapted to engage over the lugs whereby when the cap is turned on the container the disk will operate either to open communication between the cartridge and the container or close communication between the cartridge and the container, a perforated gasket located against the disk and adapted to engage the end of the container and function as an air-tight closure, and a friction means to compel the turning movement of the disk with the cap.

4. The combination with a container, lugs on the container spaced apart, a cap, a partition plate in the cap having an opening therein adapted to receive a sterilizing cartridge, a disk mounted to turn on the cap, channel-shaped fingers on the disk adapted to engage over the lugs whereby when the cap is turned on the container the disk will operate either to open communication between the cartridge and the container, or close communication between the cartridge and the container, flanges on the end of the cap adapted to engage under the lugs on the container to lock the cap in closed position on the container, a perforated gasket located against the disk and adapted to engage the end of the container and function as an air-tight closure, and a friction means to compel the turning movement of the disk with the cap.

Signed at New York in the county of New York and State of New York this 20th day of September, A. D. 1927.

HARRY MARTIN
